UNITED STATES PATENT OFFICE.

WILLIAM B. H. PEGRAM, OF ELKIN, NORTH CAROLINA.

PORTABLE LEVER OR HAND-CAR TURN-TABLE.

1,311,770.

Specification of Letters Patent.

Patented July 29, 1919.

Application filed March 29, 1919. Serial No. 286,059.

To all whom it may concern:

Be it known that I, WILLIAM B. H. PEGRAM, a citizen of the United States, residing at Elkin, in the county of Surry and State 5 of North Carolina, have invented certain new and useful Improvements in Portable Levers or Hand-Car Turn-Tables, of which the following is a specification, reference being had therein to the accompanying 10 drawings.

This invention relates to a durable lever or hand car turn table, and has for its object the construction of a simple and efficient apparatus for the placing of a hand 15 car upon a railroad track, or the quick and comparatively easy removal of a hand car from a railroad track to one side thereof.

With this and other objects in view, my invention comprises certain novel constructions, combinations, and arrangements of 20 parts as will be hereinafter specifically described, illustrated in the accompanying drawings, and more particularly pointed out in the appended claims.

25 In the drawings,

Figure 1 is a top plan view of an apparatus constructed in accordance with the present invention.

Fig. 2 is a sectional view taken on line 30 2-2, Fig. 1, looking in the direction of the arrows.

Fig. 3 is a view similar to Fig. 1, the apparatus being shown in a position for removing a hand car from the track or for 35 placing the car upon the track.

Fig. 4 is an enlarged, fragmentary, sectional view taken on line 2-2, Fig. 1, omitting the primary tie.

Fig. 5 is an enlarged, perspective view of 40 the auxiliary, rotatable plate.

Fig. 6 is a perspective view of one of the hinged, supporting arms.

Referring to the drawings by numerals, 1 comprises the primary tie and 2 the auxiliary, 45 5 ties upon which are secured the usual rails 3; these ties and rails constitute a railroad track.

50 My apparatus comprises a primary support or bed plate 4 that is provided with integral, downwardly-extending prongs 5. These prongs sufficiently penetrate the tie 1 for holding the apparatus temporarily upon the tie against accidental displacement, and if it is desired to further fasten the apparatus to tie 1, spikes 6 may be employed as additional securing means. The primary

plate 4 is provided with a central socket 7 for receiving the downwardly-extending or concavo-convex portion 8 of the auxiliary, rotatable plate 9. Both the plates 4 and 9 60 are provided with registering apertures 10 for receiving the fastening bolt 11, which bolt is provided with a nut 12 upon its threaded end.

The auxiliary plate 9 is provided with integral pairs of apertured ears 13; the ears in each pair extend upwardly, and to each pair of ears is secured a hinged, supporting arm 14. Each supporting arm 14 comprises a straight body portion 15 having 70 at its outer end hook 16, and near hook 16 is preferably a pair of horizontally-aligned apertures 17; near the inner end of the body 15 is a vertical aperture 17 (Fig. 6), and upon the inner end of body 15 is formed 75 a vertically-extending, apertured lug 18, which lug 18 has a slightly outwardly-beveled inner end 19 that engages the auxiliary plate 9 between the ears of each pair, holding the arm when folded down as shown 80 in Figs. 2 and 4 in a slightly raised position, whereby the auxiliary rails 20 are held slightly above the main or primary rails 3. The apertures of ears 13 and the aperture in the lug 18 register, and suitable fastening 85 means, as shown at 21 (Fig. 4), are placed in these registering apertures for holding the arms 14 upon the ears of plate 9. For compactness, when the apparatus is to be removed or transported, the arms 14 can be 90 folded together as indicated by the dotted positions in Fig. 4.

The outer flanges of the auxiliary rails 20 are placed under the hook 16 of the arms, and then suitable fastening means, as spikes 95 22 (Fig. 2), may be employed for securely fastening the auxiliary rails 19 upon the arms.

Bracing links 23 are employed for strengthening and stabilizing the auxiliary 100 rails 20, and each link 23 is fastened at its outer end in an integral lug 24 formed upon rail 19, and is hooked, at its inner end, into aperture 17 of arm 14.

Rails 25 can be attached to the ends of the 105 auxiliary rails 20 in any desired manner; these rails 25 constitute a switch for facilitating the running of the hand car up on to the turn table, or by detaching rails 25 at 26, the car can be left on rails 25 at one side 110 of the main railroad track.

It is to be understood that I have pro-

duced a comparatively simple, portable apparatus for placing a hand car on or off a main railroad line or track, and by reason of the peculiar construction of the arms, etc., an excellent turn table is produced, the placing of the hand car on the auxiliary rails 20 making it easy to turn or revolve the car to the position desired by the operators.

10 In manufacturing my invention, certain minor changes may appear to one skilled in the art to which this invention relates, and, therefore, I reserve the right to make such changes or alterations as shall fairly fall 15 within the scope of the appended claims.

What I claim is:

1. In an apparatus of the class described, the combination of a primary support provided with a central aperture and a central 20 socket, an auxiliary support provided with a central aperture and a central concavo-convex portion fitting into said central socket of the primary support, fastening means extending through the apertures of 25 the primary and auxiliary supports securing the same together, rails positioned contiguous to said auxiliary support, and means connecting said rails to said auxiliary support.

30 2. In an apparatus of the class described, the combination with a primary support, of an auxiliary support rotatably mounted upon said primary support, said auxiliary support provided with pairs of upwardly-extending ears, arms provided with lugs positioned between the ears, fastening means extending through the ears and through said lugs of the arms, pivotally securing the arms upon the auxiliary support, rails positioned 40 upon said arms, and means securing said rails to said arms.

3. In an apparatus of the class described, the combination with a primary plate or support, of an auxiliary support rotatably 45 mounted upon said primary support, said auxiliary support provided with ears, arms pivotally connected to said ears and provided at their inner ends with beveled, outwardly-inclined faces normally engaging 50 the auxiliary support whereby the arms are held slightly in raised positions, and rails secured to said arms.

4. In an apparatus of the class described, the combination with a support, of an auxiliary plate rotatably mounted upon said support, said auxiliary plate provided with pairs of parallel, upwardly-extending lugs, arms provided at their inner ends with upwardly-extending apertured lugs, the lugs 60 of the arms positioned between the ears, each lug provided with an outwardly beveled face adapted to engage the auxiliary plate between the ears for holding the arm in a

relatively raised position, fastening means 65 extending through the ears and the lugs of the arms for securing the arms upon the auxiliary plate, and rails secured to said arms.

5. In an apparatus of the class described, the combination with a support, of a plate 70 rotatably mounted upon said support, arms pivotally connected to said plate, rails resting upon said arms, bracing links connected at their inner ends to said arms and connected at their outer ends to said rails, and means 75 supported by the arms for securing and fastening the rails thereto.

6. In an apparatus of the class described, the combination with a support, of a rotatably-mounted plate carried by said support, arms hingedly connected to said plate and provided with means at their inner ends whereby they are retained normally in a slightly raised or inclined position, and 80 rails supported upon said arms.

7. In an apparatus of the class described, the combination of a primary plate provided with integral depending prongs and with a central socket and an aperture, an auxiliary plate having a concavo-convex 90 portion fitting the socket of the primary plate, said auxiliary plate provided with a central aperture registering with the aperture of the primary plate, a bolt extending through said registering apertures of the 95 primary and auxiliary plates and connecting the same together, said auxiliary plate provided at its opposite sides with upwardly-extending apertured ears, the ears arranged in pairs, an arm having an upwardly-extending apertured lug positioned 100 between the ears of each pair, fastening means extending through the ears of each pair and the lug for pivotally securing the arm upon the auxiliary plate, each arm provided 105 contiguous to the lug with a downwardly and outwardly-extending beveled face adapted to engage the auxiliary plate for holding the arm in a slightly raised position, each arm provided at its outer end 110 with a hook and near said hook with a pair of transversely-aligned apertures, rails carried by said arms and engaging the hooks, fastening means extending through the transversely-aligned apertures of the arms 115 and securing the rails upon the arms, each rail provided with an apertured lug on its inner face, and bracing links secured at their outer ends in the apertured lugs of the rails and having their inner ends extending 120 through the arms near their inner ends, substantially as shown and described.

In testimony whereof I hereunto affix my signature.

WILLIAM B. H. PEGRAM.
